CLAIM

The ornamental design for a combined nebulizer head and adapter, as shown and described.

DESCRIPTION

FIG. 1 is a top, rear perspective view of a combined nebulizer head and adapter, showing my new design; FIG. 2 is a bottom, front, right perspective view thereof;

FIG. 3 is a top plan view thereof;

FIG. 4 is a left side elevational view thereof;

FIG. 5 is a front elevational view thereof; and

FIG. 6 is a bottom plan view thereof.

The broken away showing of the tube portion in FIGS. 4 and 5 is for ease of illustration.

*FIG. 3.**FIG. 4.**FIG. 5.**FIG. 6.*
